UNITED STATES PATENT OFFICE.

JOSEPH J. WISNIEWSKI, OF CHICOPEE, MASSACHUSETTS.

DESIGN FOR A TIRE TREAD.

Application filed July 11, 1923. Serial No. 6,756. Term of patent 7 years.

To all whom it may concern:

Be it known that I, JOSEPH J. WISNIEWSKI, a citizen of the United States of America, residing at Chicopee, in the county of Hampden and State of Massachusetts, have invented a new, original, and ornamental Design for Tire Treads, of which the following is a specification, reference being had to the accompanying drawings, forming a part thereof.

In the drawings, Figure 1 is a top plan of a portion of a tire tread, showing my new design, and, Fig. 2, a cross section taken on lines 2—2, looking in the direction of the associated arrow, in Fig. 1.

I claim:

The ornamental design for a tire tread, as shown.

JOSEPH J. WISNIEWSKI.
